UNITED STATES PATENT OFFICE.

ENOCH HENDERSON, OF HOUGHTON, MICHIGAN.

CIRCULAR SORTING OR CONVEYING TABLE.

1,184,528.

Specification of Letters Patent. Patented May 23, 1916.

Application filed November 13, 1915. Serial No. 61,343.

To all whom it may concern:

Be it known that I, ENOCH HENDERSON, a citizen of the United States, and a resident of Houghton, in the county of Houghton and State of Michigan, have invented a new and Improved Circular Sorting or Conveying Table, of which the following is a full, clear, and exact description.

My improved table is designed more particularly for use at mines in picking or sorting barren rock out of ore, but is useful in the sorting of other ores and as a conveyor. The table is mounted to be revolved and ore is fed thereto so as to be carried as the table revolves past workmen stationed about the table to pick out the barren rock. A deflector, which is termed a plow, is disposed above the table in the path of movement of the material being sorted and upon reaching the plow the material is swept from the table either to the inside or to the outside thereof. The plow or deflector, is sustained in position in a manner to be readily and conveniently displaced where desired and whereby the inertia of the plow is effectively utilized in preventing accidental displacement of the plow.

Furthermore, in the preferred form of the invention, the position of the plow relatively to the feed chute is such that the material being received and the material being swept from the table will act on opposite sides of the plow to counter-act the pressure at opposite sides. Also, the particular form of the plow in the preferred construction is characterized by strength and simplicity, and results in an effective sweeping of the material from the table.

The invention will be particularly explained in the specific description following.

Reference is to be had to the accompanying drawings forming a part of this specification in which similar reference characters indicate the corresponding parts in all the views.

Figure 1 is a plan view of a circular table embodying my invention; Fig. 2 is a transverse vertical section on the line 2—2, Fig. 1; Fig. 3 is a detail transverse vertical section on the line 3—3, Fig. 1; and Fig. 4 is a transverse vertical section on the line 4—4, Fig. 1.

In constructing a practical embodiment of my invention in accordance with the illustrated example, a suitable base 10 is pro-

vided, having a circular track 11 thereon, on which the circular table 12 in the form of a ring is mounted to turn on ball bearings 13. A feed chute 14 leads to the table at one side and a deflector or plow, designated generally by the numeral 15 is suitably placed on the table and preferably disposed adjacent to the chute 14. In the present example, the plow is arranged to sweep the material from the table at the inner periphery of the latter to a chute 16 which may lead to a crusher or other apparatus or receptacle.

The track 11 is formed with flanges 17 at each side to receive securing bolts 18, Fig. 4. The track 11 has a concave depression 19 in its upper surface and an opposed annular groove or depression 20 is formed in the underside of the table 12, whereby to constitute with the groove or depression 20, an annular race for the balls 13. In practice, the balls 13 are cast iron and are placed in sufficient numbers to substantially fill the ball race.

The table 12 is made in the form of upper and lower rings, the lower ring 21 being separately formed and secured to the upper ring or table top by bolts 23, or the like. Both the upper and lower rings may be formed in any number of segments, there being indicated, (see Fig. 1), six segments in each ring, and the segments of the respective ring breaking joint. The lower ring 21 is the narrower and has side flanges 22 to receive the bolts 23. At the inner periphery of the lower ring 21, a depending annular flange 21^a is formed to exclude dirt from the ball race and to prevent the axis of the table from moving horizontally which might result in the displacement of the table from its bearings.

The table 12 may be given motion by any suitable means. In the preferred arrangement, a pinion 24 on a driven shaft 25 meshes with a circular rack 26 cast on the lower ring 21, the said shaft being driven from any convenient source of power. The manner of forming the table 12 with the upper and lower rings enables me to employ cast iron and the same is true of the track 11 and the ball bearings 13. At the same time any renewal of parts of the table involves the minimum expense. The castings forming the table and track are rough castings and not machined, the form of the parts and the character of the drive employed permit-

ting these rough castings to be employed with good results.

In practice, the deflector or plow 15 is advantageously formed of a piece of timber.

- 5 On the said timber at the back or outer face thereon, a wear plate 27 of sheet metal is secured to take the wear of the material coming from the chute 14, the said plow being arranged above the table across the path 10 of movement of the material and oblique to the said path of movement and oblique to the chute 14. On the face of the timber a shoe 28 is applied, the same being longitudinally curved so as to present its concave side 15 to the path of movement of the material, as clearly shown in Fig. 1, in which figure the arrows indicate the direction of movement of the material, it being understood that the table is turned contra-clockwise with the arrangement shown, but may be turned clockwise with a reversal of the deflector. At the back of the shoe 28, between the same and the timber a sheet metal plate 29 is provided projecting above the shoe and contributing to the strength thereof as well as forming a wear surface for the front side of the timber.

The inertia of the plow or deflector is utilized in retaining the plow in position 30 and the upper surface of the plow is adapted to receive weights 30, 31. In the illustrated form of the apparatus, the plow is suspended by a series of chains, indicated at 33, said chains being preferably connected 35 with the plow at both ends of the timber and an additional chain at the end of the curved shoe 28. The chains permit the plow to be adjusted at any desired distance from the surface of the table 12. There may also 40 be employed guys or tie chains 34, 35 secured to the plow near each end and fixedly secured at the opposite ends to any convenient fixed members or supports. I have shown eyes 36 on the plow to receive the 45 chains 33, there being provided a shackle 37 on the plow at one end to connect with the chains 34, and an eye 38 rear the opposite end of the plow to connect with the chain 35. I prefer to position the plow or deflector 50 or 15 adjacent to the delivery chute 14 so that the material will be carried practically through a complete circle before being discharged. Also, in this way, the pressure of the material being carried against the 55 front of the plow will be largely counterbalanced by the pressure of the material being received from the chute 14 at the back of the plow. The various chains may have

turnbuckles 40 or other means for effecting adjustment.

Having thus described my invention I claim as new, and desire to secure by Letters Patent:

1. An apparatus of the class described, including a table in the form of a ring and mounted to turn on its own axis, means to give a traveling motion to said table on its axis, means to deliver material to the table, and a deflector extending over the ring at a side thereof across the path of movement of the material carried by the table, and adapted to sweep the material from the table over a peripheral edge thereof, said deflector comprising a beam presenting a top surface adapted to receive weights, the front face 75 of the beam being longitudinally curved, a shoe secured to the face of the beam and extending in curved form beyond the outer end of the beam and beyond the table, suspension means connected with the beam 80 at the inner end, and suspension means connected with the said projecting outer end of the curved shoe.

2. An apparatus of the class described, including a table in the form of a ring, 85 means to give a turning movement to the said table on its axis, a chute for delivering material to the table at one side of the ring, and a deflector positioned at the upper side of the said table and extending across the 90 path of movement of the material in front of the chute and oblique to the said path of movement of the material.

3. An apparatus of the class described, including a table in the form of a ring, 95 means to give a turning movement to the said table on its axis, a chute for delivering material to the table at one side of the ring, and a deflector positioned at the upper side of the said table and extending across the 100 path of movement of the material in front of the chute and oblique to the said path of movement of the material, the said deflector presenting its concave side at the front to receive the contact of the material carried 105 by the table, the back of the deflector being disposed toward the chute to receive the contact of the material discharged by the chute.

In testimony whereof I have signed my 110 name to this specification in the presence of two subscribing witnesses.

ENOCH HENDERSON.
